Specification for Design.

Patented Oct. 26, 1915.

Application filed April 24, 1915. Serial No. 23,759. Term of patent 7 years.

To all whom it may concern:

Be it known that I, JOHN J. NASH, a citizen of the United States, residing in Waterbury, in the county of New Haven and State of Connecticut, have invented a new, original, and ornamental Design for a Neck for Bed-Trimmings, of which the following is a specification, when taken in connection with the accompanying drawing.

In the drawing, Figure 1 is a side eleva-

tion of a neck for bed trimmings embodying my design; and Fig. 2 is a top plan view of the same.

What I claim is:—

The ornamental design for a neck for bed trimmings, substantially as shown.

JOHN J. NASH.
